BRUNO V. NORDBERG, OF MILWAUKEE, WISCONSIN, ASSIGNOR TO THE NORDBERG MANUFACTURING COMPANY, OF SAME PLACE.

STATIC GOVERNOR.

SPECIFICATION forming part of Letters Patent No. 663,298, dated December 4, 1900.

Application filed March 8, 1899. Serial No. 708,235. (No model.)

To all whom it may concern:

Be it known that I, BRUNO V. NORDBERG, a citizen of the Grand Duchy of Finland, Russia, residing at Milwaukee, in the county 5 of Milwaukee and State of Wisconsin, have invented certain new and useful Improvements in Static Governors, of which the following is a specification, reference being had to the accompanying drawings, forming a part 10 thereof.

My invention relates to governors for automatically changing the speed of an engine under a substantially constant load as distinguished from governors for maintaining a 15 substantially constant speed under a variable load. It is particularly applicable to pumping-engines or compressors.

The main objects of the invention are to render governors of the class first mentioned 20 more sensitive or responsive and generally to improve their construction and operation.

It consists in certain novel features in the construction and arrangements of parts, as hereinafter particularly described, and pointed 25 out in the claims.

In the accompanying drawings like letters designate the same parts in the several figures.

Figure 1 is a plan view and partial horizontal section of the governor proper. Fig. 2 is 30 a vertical section on the line 2 2, Fig. 1. Fig. 3 is a similar section on the line 3 3, Fig. 1; and Fig. 4 is a side elevation of the governor, including the adjustable regulating connection or mechanism employed in connection 35 therewith, certain parts of the regulating mechanism being broken away and shown in section.

A designates a tubular governor-stand in 40 which the vertical rotary shaft B is supported in suitable bearings. Upon the upper end of the shaft B is pinned or otherwise secured a sleeve or cross-head C, formed or provided on opposite sides with forked arms D D. From 45 these arms are centrally suspended rolling weights E E by links F F. Two pairs of cone-shaped weights are shown, one pair suspended by and on opposite sides of each link. The links are formed at their outer or lower 50 ends, as shown in Fig. 3, with sleeves f, through which the rods e, carrying said weights, pass

horizontally, the weights being centrally bored and pivoted or journaled on these rods.

G is a cylindrical case formed or provided with a central hub or sleeve g, which is 55 loosely mounted upon the shaft B between the stand A and the sleeve C. It has a cover-plate H screwed or otherwise fastened thereon and formed with a central hub or sleeve h, which also loosely encircles the shaft B. On 60 the under side of this cover-plate are formed planed ways h' h', which rest upon the peripheries of the weights E. This plate is also provided on opposite sides of the center with depending pins I I or vertically-disposed projections which are arranged to bear against the peripheries of rollers j j, journaled on rods or arms J J, extending horizontally from opposite sides of the sleeve C at right angles to the arms D D. By this means the case G and 65 its cover are caused to turn with the shaft A and weights E and are allowed to rise and fall freely upon said shaft. The weights E are turned true, and being centrally pivoted or journaled upon the rods e and freely suspended by the links F have a free rolling contact with the cover-plate H, resting thereon, thereby avoiding frictional resistance to 70 their movement and rendering the governor more sensitive or responsive to variations in 75 speed.

While the construction and arrangement of the weights and their connections with the governor-shaft, shown and described, are considered preferable, they may be made of various other form, and their connections may be changed without material effect upon their operation—for example, a single weight of cylindrical or other form may be substituted for the two conical weights on each side of 80 the governor-shaft, and each weight may be suspended by a forked link or a pair of links. The construction of the case which incloses and rests upon the weights may also be modified in various ways without affecting the result—as, for example, the body or lower portion G of said case may be dispensed with and the plate H may be connected by rods or otherwise with the sleeve g, through which the regulating connection with the valve-gear 85 90 of the engine is made. This regulating connection may be variously constructed and ar-

ranged, either for manual or automatic adjustment, or both, to adapt the governor to the different conditions or uses to which the engine is applied.

- 5 Referring to Fig. 4, which shows one form of adjustable regulating connection or mechanism between the governor proper and the valve-gear of the engine, K is a floating lever consisting in the present instance of two parallel horizontally-disposed bars pivotally connected with opposite sides of a collar k, in which the sleeve g or other vertically-movable part of the governor is free to turn, as shown in Fig. 2. One end or arm of this lever 15 is connected by the rod L with the valve-releasing or cut-off mechanism of the engine (not shown) by a system or train of rods and levers comprising a rod L, bell-crank lever M, and rod N, or by other suitable means. 20 The rod L may be made in two sections having reverse screw-threads and connected by a right and left threaded nut l, by which said rod may be manually lengthened or shortened for the purpose hereinafter explained. O is 25 a cylinder closed at its upper end and supported in a vertical position parallel with the shaft B by a bracket a on the governor-stand. P is a plunger fitted in said cylinder and projecting therefrom through its lower open end. 30 The plunger P is connected on each side of the cylinder O by a rod p with the end or arm of lever K opposite that with which the valve-gear is connected. The upper end of the cylinder O is connected by a pipe o with the discharge chamber or conduit of the pump or with any passage or reservoir containing fluid, the volume or pressure of which is governed or affected by the operation of the pump. The lower end of said plunger is formed or 35 provided with a pin bearing centrally against the bottom of a flanged cup which rests upon the upper end of a spiral spring Q, supported in turn at its lower end upon an inverted flanged cup q', which bears centrally upon 40 the point of an adjusting-screw R. This screw is carried in line with the plunger P by a spider S, suspended by rods s from the bracket a. A forked or double lever T, having a spring fulcrum connection t with the 45 governor-stand, is pivotally connected at one end with opposite sides of the plunger P at its lower end and by the rods p with the lever K. An adjustable weight U is suspended from the other end of said lever. V is a dash- 50 pot supported by an extension of the bracket a, parallel with the cylinder O. In it is fitted a plunger which is connected by a rod v with laterally-projecting arms p' on the rods p.

The governor and its adjustable regulating 60 connection with the valve-gear, as shown and hereinbefore described, operates as follows: By an increase in the speed of the engine and of the shaft B, which is connected therewith in any suitable manner, the weights E are 65 thrown outward and upward by centrifugal force, thereby raising the gear case or plate H and the sleeve g, which carries the collar

k, to which the lever K is fulcrumed or pivoted. A decrease in the speed of the governor allows the weights and the case to descend by gravity. In these movements the weights roll freely without friction against the ways h' on the under side of the cover-plate H, which, with the case G, serves as a counterpoise, and the rollers j, engaging the pins I, turn the case and at the same time permit it to freely move up and down with the weights. A comparatively limited range in the movement of the weights and of the counterpoise resting thereon admits of a wide variation in the speed of the engine to which the governor is applied. The spring Q and the weight U being adjusted for any given pressure that the pump or compressor is to maintain and the parts of the regulating connection or mechanism occupying under such pressure the relative positions shown in Fig. 4, whenever a slight increase of pressure occurs it will be communicated through the pipe o to the cylinder O and will force the plunger P downward against the tension of spring Q and the opposing weight U. The lever K will thus be swung slightly on its pivot connection with the collar k as a fulcrum, so as to shift the rod N in the direction indicated by the arrow 1 and cause an earlier release of the steam-valves or an earlier cut-off. When this occurs, the engine slows down, and the weights E in consequence descend slightly, carrying with them the case G or counterpoise and the lever K, which now turns on its pivot connections with rods p as a fulcrum until the valve-releasing or cut-off mechanism is returned to its original position or the normal cut off of the engine is restored. The engine will now 105 continue to run at a slower rate of speed until the pressure against which the pump is working is again slightly varied. If it is lowered, the diminished pressure in the cylinder O allows the spring Q, aided by the weight U, to force the plunger P upward and to swing the lever K on its pivot connection with the case G or counterpoise, and thereby shift the rod N in the proper direction (indicated by the arrow 2) to produce a later cut-off. The engine being thus supplied with more steam increases in speed, thereby causing the governor-weights to rise and lift the case G or counterpoise and to turn the lever K on its pivot connections with rods p until the valve-releasing or cut-off mechanism is returned to its original position or the normal cut-off of the engine is restored. The engine will continue to run at this higher speed until another change, either a rise or fall, in the pressure produced or affected by the pump takes place.

The regulating mechanism is adjusted so that the engine and pump or compressor will produce and maintain a greater or less pressure by varying the tension of the spring Q by means of the adjusting-screw R, or by varying the weight U, which is made in sections for this purpose, or by varying both the

tension of the spring and the weight. When the foregoing adjustment has been made for any given pressure, the connection between the governor and valve-gear may be adjusted 5 by lengthening or shortening the rod L, so that the plunger P will stand when subjected to that pressure in any desired position either at the upper limit of its movement or at some point below.

By the employment of a weight which opposes a constant resistance to the movement of the plunger P by the fluid-pressure in cylinder O in connection with a spring Q, which affords a variable resistance to such movement, a weaker spring may be employed. Therefore a smaller variation in the pressure is caused to change the speed of the engine than would be required to produce such change if the spring alone were used, and hence a more uniform and constant pressure may be maintained.

By the use of a comparatively weak spring in connection with the weight a gradual change is effected in the cut-off of the steam- 25 valves, and consequently a gradual change in the speed of the engine whenever a slight or gradual change in the pressure produced by the pump or compressor takes place, whereas if a weight which opposes a constant resist-

ance to the movement of the plunger P were used alone a slight change in pressure sufficient to start said plunger would carry it to the extreme limit of its movement in either direction, and thereby shift the cut-off mechanism to the extreme limit of its adjustment and produce a sudden and extreme variation in the speed of the engine.

Where water supplied by a pumping-engine is used for extinguishing fires, and for that purpose a higher pressure or head has to be temporarily maintained, an extra weight may be suspended from the weight U. This will have the effect of increasing the head or pressure maintained by the pump and of increasing the speed of the engine if necessary to maintain such pressure or head.

The dash-pot V is employed to prevent overthrow and wavering of the plunger and its connections, particularly when the pump operates upon an elastic fluid or gas, such as air. With inelastic fluids or liquids, such as water, it may be dispensed with.

By the term "floating lever" as herein employed is intended a lever which has a shifting or movable fulcrum.

The governor, valve-gear, and manual or automatic adjusting device may be connected with said lever in any order—that is, both the valve-gear and adjusting device may be 60 connected on one and the same side of the governor connection, and either the valve-gear connection or the adjusting device connection may be made between the other two. In place of the cylinder and plunger O and

P other automatic adjusting devices may be substituted for varying the speed of the engine, according to change in volume or pres-

sure of the fluid upon which the pump operates, either on the suction or discharge side. For example, a float in a reservoir, into which the pump discharges, or in a well or sump, from which the pump draws liquid, may be connected with the floating lever, so that slight variations in the level of the liquid will produce the same effect upon the regulating 70 connection between the governor and valve-gear as is produced by variations of fluid-pressure on the plunger P. For manual adjustment alone a connection like that between the levers K and M may take the place 75 of the cylinder and plunger O and P.

It is obvious that the arrangement of cylinder O and plunger P may be reversed—that is, the cylinder may be movable and connected with the lever K and the plunger may be 85 connected with a stationary support. In short, various changes in the details of construction and arrangement of parts other than those hereinbefore pointed out may be made without material effect upon the operation of 90 the governor and without departure from the principle and intended scope of my invention.

In connection with governors of the class to which my invention relates a substantially constant steam-pressure should be main- 95 tained.

I claim—

1. In a static governor the combination with the governor-shaft provided with oppositely-projecting arms, of rolling weights having circular bearings, links centrally pivoted to said weights and connecting them with said arms, and a vertically-movable counterpoise resting with a rolling contact upon said weights, substantially as and for the purposes set forth. 100

2. In a static governor the combination with a vertical rotary shaft, of a vertically-movable counterpoise loosely mounted upon said shaft, and vertically-swinging weights centrally connected with said shaft and having a rolling 110 contact with said counterpoise which rests upon them, substantially as and for the purposes set forth.

3. In a static governor the combination of a vertical rotary shaft, a sleeve fixed thereon 115 and provided with oppositely-projecting lateral arms, rolling weights suspended from said arms by links to which they are centrally pivoted or journaled, and a vertically-movable counterpoise resting upon said weights 120 and provided with projections loosely engaging arms on said shaft, substantially as and for the purposes set forth.

4. In a static governor the combination of a vertical rotary shaft having laterally-projecting arms provided with rollers, a vertically-movable counterpoise having vertical pins or projections adapted to bear against said rollers, and round weights centrally suspended by links from opposite arms on said 130 shaft and having a rolling contact with said counterpoise which rests thereon, substantially as and for the purposes set forth.

5. The combination with a static governor

of an adjustable regulating connection between said governor and the valve-gear of a pumping-engine, comprising a floating lever having a movable pivot on which it swings as a fulcrum when actuated by the governor, means for automatically shifting said pivot according to variations in volume or pressure of the fluid which the pumping-engine operates upon, substantially as and for the purposes set forth.

6. The combination of a static governor comprising a rotary shaft, weights centrally suspended by links from arms on said shaft, and a movable counterpoise resting upon said

15 weights which have a rolling contact therewith, and an adjustable regulating connection between said counterpoise and the valve-gear of a pumping-engine, comprising a floating lever having a movable pivot on which it 20 swings as a fulcrum when actuated by the governor, and means for adjusting said pivot to vary the speed of the engine, substantially as and for the purposes set forth.

7. The combination with a static governor 25 of an adjustable regulating connection comprising a floating lever pivotally connected with a movable part of the governor and also connected with the valve-gear of a pumping-engine, a cylinder and plunger, one of which 30 is connected with said lever, a fluid connection for communicating to said cylinder and plunger the pressure by which the operation of the pumping-engine is controlled or regulated, and resistance opposing the movement 35 of said lever by the fluid-pressure acting through said cylinder and plunger, substantially as and for the purposes set forth.

8. The combination with a static governor of an adjustable regulating connection comprising 40 a floating lever pivotally connected with a movable part of the governor and also connected with the valve-gear of a pumping-engine, a cylinder and plunger, one of which is connected with said lever, a connection 45 with said cylinder and plunger for communicating thereto the fluid-pressure by which the operation of the pumping-engine is controlled or regulated, and an adjustable resistance opposed to the movement of said lever by the 50 fluid-pressure acting through said cylinder and plunger, substantially as and for the purposes set forth.

9. The combination with a static governor, of an adjustable regulating connection comprising 55 a lever connected with the governor and with the valve-gear of the engine, a cylinder and plunger, one of which is connected with said lever, a fluid-pressure connection with said cylinder, and a spring and weight 60 acting upon said lever in opposition to the

fluid-pressure in said cylinder, substantially as and for the purposes set forth.

10. The combination with a static governor, of an adjustable regulating connection comprising a floating lever pivotally connected 65 with a movable part of the governor and also connected with the valve-gear of a pumping-engine, a cylinder and plunger, one of which is connected with said lever, a fluid-pressure connection with said cylinder, and an adjustable spring and adjustably-weighted lever opposing the movement of said lever by fluid-pressure, substantially as and for the purposes set forth.

11. The combination with a static governor, 70 of a floating lever having a pivot connection with the governor and also connected with the valve-gear of a pumping-engine, a cylinder and plunger, one of which is connected with said lever, a fluid-pressure connection 75 with said cylinder, a resistance opposed to the movement of said lever by fluid-pressure, and a dash-pot having a plunger which is connected with said lever, substantially as and for the purposes set forth.

12. The combination with a static governor, 80 of a floating lever having a pivot connection with the governor, and also connected with the valve-gear of a pumping-engine, a vertically-disposed stationary cylinder closed at 85 its upper end and having a fluid connection with the discharge-conduit of the pumping-engine, a plunger fitted in said cylinder and connected by rods on opposite sides thereof with said lever, an adjustable spring, and an 90 adjustably-weighted lever pressing upwardly against said plunger in opposition to the fluid-pressure in said cylinder, substantially as and for the purposes set forth.

13. The combination with a static governor 100 comprising rolling weights centrally pivoted or journaled to and suspended by links from arms on a vertical rotary shaft, and a vertically-movable counterpoise resting upon said 105 weights, of an adjustable regulating connection comprising a floating lever having a pivot connection with said counterpoise and also connected with the valve-gear of a pumping-engine, a cylinder and plunger, one of which is connected with said lever, a fluid-pressure 110 connection with said cylinder, and a resistance opposed to the movement of said lever by the fluid-pressure in said cylinder, substantially as and for the purposes set forth.

In witness whereof I hereto affix my signature in presence of two witnesses.
